ELECTRIC SWITCH

Gordon H. Clark, Pottstown, Pa., assignor to
 Hoffman Gas & Electric Heater Company,
 Louisville, Ky., a corporation of Delaware

Application November 11, 1935, Serial No. 49,242

3 Claims. (Cl. 200—137)

This invention relates to improvements in an electric switch having reference particularly to a thermostatically controlled switch for connecting and disconnecting the heating coil circuits in a two-coil system.

One of the objects of the invention is the provision of an efficient double electric switch adapted to be actuated by a thermostat, particularly a thermostat of the tubular type, so as to close or open two electric circuits in succession when the temperature change affects the entire length of the thermostat, and to close or open one of said circuits only when the temperature change affects but one portion of the thermostat.

Other objects and features of novelty will appear as I proceed with the description of that embodiment of the invention which, for the purposes of the present application, I have illustrated in the accompanying drawings, in which Fig. 1 is an elevational view, partly broken away and partly in section, showing a water tank with my electrical heating means installed therein.

Fig. 2 is a diagram of the electric circuits.

Fig. 3 is a plan view of the double switch which I employ in connection with the invention.

Fig. 4 is a side view of the same.

Fig. 5 is a transverse sectional view taken substantially on the line 5—5 of Fig. 4 showing the switch in position to connect the lower heating coil with its energizing circuit.

Fig. 6 is an end view of the switch.

Fig. 7 is a longitudinal sectional view taken substantially on the line 7—7 of Fig. 3.

Fig. 8 is a bottom plan view taken substantially on the line 8—8 of Fig. 7, and

Fig. 9 is a detail view of one of the snap levers of the switch.

In Fig. 1 of the drawings there is illustrated a metallic water tank 10, preferably in the form of a vertical cylinder, which is surrounded by a cylindrical metallic casing 11, spaced from the tank 10, with suitable insulation 12 interposed between the tank and the casing. 13 is a valved draw-off connection. Cold water is admitted to the tank 10 through an intake pipe 14 located near the bottom of the tank, while at the top of the tank there is a hot water delivery pipe 15. In the upper end of the tank 10 there is a central opening 16 in which there is mounted and welded a collar 17 that forms a seat for metal plate 18. A gasket 19 is placed in the joint between this collar and plate, and the latter is fastened down by a series of studs 20.

On the top of the casing 11 there is a flanged

metal cover 21 which has a circular opening in the middle thereof. The inner edge of the cover 21 meets a cylindrical, preferably non-metallic, member 22 that surrounds the collar 17 and serves to confine that part of the insulation 12 which overlies the top of the tank 10. 23 is a metal disk with a depending annular rib 24 which extends down into the central opening in the cover 21. The disk 23 is held in place by nuts on the upper ends of studs 25 which extend upwardly from the plate 18 in which they are anchored. Finally, above the disk 23 there is a metallic cap 26 containing insulation 27 and having a bottom rim by means of which the cap is secured onto cover 21.

The heating unit depends from and is supported by the plate 18, the latter serving also as a closure for the tank. In the present instance the heating unit is shown as comprising a tube 28, preferably of copper, having a water-tight connection with the plate 18 and having a cap 29 at its lower end joined to the tube by a water-tight connection. Within the tube there is an upper heating coil 30 and a lower heating coil 31, with electrical connections extending upwardly to the top of the tube and into the space above plate 18.

The tube 28 is preferably located axially of the tank, that being the most efficient position for the heating coils. Alongside the tube 28, but spaced therefrom to permit free circulation of water, there is a thermostat 32. While in some aspects of the invention the particular character of the thermostat is not of importance, I prefer to utilize one of the type illustrated which consists of an outer tubular member 33 (see Fig. 7) formed of metal having a high coefficient of expansion, and an inner rod 34 formed of metal having a low coefficient of expansion. The tube 33 is preferably threaded into an opening in the plate 18, and the rod 34 projects upwardly through 40 and beyond that opening. The tube 33 and rod 34 are secured together at their lower ends. The thermostat is guided near its lower end in a bracket 35 which has a circular opening therein to receive the thermostat loosely. The guide 45 bracket 35 serves to steady the thermostat 32, and is especially useful on that account during transportation of the tank. It will be apparent that when the temperature of the water in the tank 10 rises the tube 33 will expand lengthwise, 50 causing the upper end of the rod 34 to descend, while cold water entering the tank will contract the tube 33, thereby causing the rod 34 to rise.

It will be noted that the cold water intake pipe 55

- 14 terminates substantially beneath the lower end of thermostat 32, so that the introduction of cold water into the tank, as hot water is drawn out, affects the thermostat almost immediately.
- 5 Near the top of the tank outside the casing 11 there is an electric junction box 36, from which conductors 37 and 38 extend inwardly to the control switch which is mounted on the plate 18 and which will now be described by reference 10 to Figs. 3 to 8 inclusive in connection with the wiring diagram of Fig. 2.

The switch comprises a metallic frame member which consists of a base 39, an upright 40, and a shelf 41, all integral. In the base there may 15 be formed a pair of holes 42 for the reception of fastenings by means of which the switch is secured to the plate 18. The upright 40 about midway of its height is deformed to provide V-groove 43 which serves as a fulcrum for one end of an 20 angular lever 44 that may be termed the operating lever. This lever has a knife edge at its inner end that seats in the V-groove 43. In the lever 44, spaced a short distance from its fulcrum, there is a threaded opening in which is received the 25 threaded lower extremity of an adjusting post 45. This post has a socket in its lower end into which the upper extremity of thermostat rod 34 extends. The post 45 projects through a slot 46 in the shelf 41 and through a similar slot in a plate 47 which 30 is secured to the upper surface of shelf 41 by a pair of shouldered studs 48, which have the additional function of stops for limiting the motion of a pointer 49 that is mounted on the upper end of the post. The pointer 49 also serves as a convenient 35 means for grasping the post 45 in order to rotate it. It will be apparent that when the post 45 is turned down, the effective point of contact between the lever 44 and the rod 34 is lowered, while the turning of the post 45 in the opposite direction raises the effective point of contact between the lever and the rod 34. In order to hold 40 the lever 44 firmly against the rod 34 I provide a coil spring 50, the upper end of which engages the shelf 41, and the lower end of which engages 45 a washer 51 resting upon lever 44 surrounding the post 45.

On the outer extremity of lever 44 I mount, by means of screws 52 and 53, a triangular block 54 of insulating material, and in this block on 50 either side of the lever holes are provided through which threaded pins 55 and 56 extend. On the upper ends of these pins there are nuts 57, by means of which the height of the pins may be adjusted. In practice they are adjusted to different heights, as indicated in Fig. 6, for a purpose which will presently appear.

A block of insulation 58 is secured to the base 39 by screws 59. On the inner ends of this block there are mounted two sheet metal conductor 60 brackets 60 and 61 which are C-shaped in vertical section with their open sides facing each other. These brackets are held in place partly by two screws 62 and 63, and partly by shouldered insulation bushings 64 and 65 that are held in 65 position by bolts 66 and 67, the upper ends of which are provided with silver contact buttons 68 and 69 respectively. Contact buttons 70 and 71 are secured to the under sides of the top portions of the brackets 60 and 61. From the lower arm 70 of the bracket 61 there extends laterally an integral lip 72, in which is mounted a screw 73 for securing a wire conductor. On the opposite end of the block 58 there are mounted two separated metal plates 74 and 75. Above these plates 75 there are thin spring metal plates 76 and 77.

Sheet metal brackets 78 and 79 rest upon the plates 76 and 77 respectively. The parts 74, 76 and 78 are fastened together and to the block 58 by means of screws 80 and 81. Similar fastenings for the parts 75, 77 and 79 are used, but not separately illustrated herein. The upright portions of the brackets 78 and 79 are bifurcated, and each of the bifurcations is deformed to provide a V-groove 82, all four of these grooves being in alignment. The thin metal plates 76 and 77 constitute the anchoring portions of two double leaf springs 83 and 84 which are curved upwardly and forwardly and have their forward portions secured to the upper sides of a pair of snap levers 85 and 86 respectively. The rear ends of these levers are 10 bifurcated, as will appear particularly from Fig. 9, and the bifurcations are received in the V-grooves 82. They are held against sidewise movement largely by the springs 83 and 84, which are secured to the levers not only at the forward end of the latter but also at points near the rear ends of the bifurcations. Coil springs 87 and 88 are positioned in the bifurcations of the levers 85 and 86 respectively and extend between the bifurcations of the brackets 78 and 79, 20 these springs having hooked forward ends that are received in holes in the levers and hooked rear ends that embrace reduced diameter portions on the lower ends of pins 55 and 56. At the forward ends of the levers there are double contact buttons 89 and 90 electrically and mechanically joined to the levers and to the leaf springs, and presenting good contact surfaces both above and beneath the levers. Integral lips 91 and 92 extend laterally from the plates 74 and 75 respectively, and have screws 93 and 94 respectively mounted therein, by means of which wire conductors may be secured, the current being carried through the leaf springs 83 and 84 to the levers 85 and 86 and the contact buttons 89 and 90.

In the under side of the insulation block 58 a diagonal groove is formed in which is positioned a metallic shunt strip or bar 95, which is secured at its ends to the screw 62 and the bolt 67.

The rear ends of the coil springs 87 and 88 are positioned near the height of the fulcrums of levers 85 and 86. When the lever 44 is lowered by the expansion of thermostat tube 33, the rear ends of the springs 87 and 88 are lowered and the forward extremities of the levers 85 and 86 are drawn down upon their abutments or contact plates 68 and 69. As the tube 33 contracts however, raising the rod 34 and swinging the operating lever 44 upward, the rear ends of the springs 87 and 88 pass over or above the fulcrums of the levers 85 and 86, thereby snapping those levers into their upper positions, where they contact with the contact buttons 70 and 71. In the usual adjustment of the pins 55 and 56 this snap-over of the levers 85 and 86 takes place at different times in the movement of the thermostat. However, if it should be desired to make the two levers move simultaneously, this can be accomplished by positioning them at the same height in the insulation block 58.

Referring to Fig. 2, it will be seen that upper heating coil 30 is connected to conductor bracket 61 and contact button 71 through the lip 72 on 70 the bracket, while the opposite end of the coil is connected by a conductor 96 with line wire 31. Lip 92 is connected with line wire 38, while lip 91 is connected by a conductor 96 with one end of the lower heating coil 31, the opposite end of 75

this coil being connected by conductor 97 with line wire 37.

Operation.—When the pins 55 and 56 are set substantially as indicated in Fig. 6, which is the position for these pins in the usual installation, the operation will be substantially as follows: Assuming that the tank is filled with cold water, operating lever 44 of the switch will be in its raised position, due to the contraction of thermo-stat tube 33. Both snap levers 85 and 86 will also be in their raised positions, or as indicated in Fig. 2, where the buttons 89 and 90 are shown in contact with the buttons 70 and 71. Current will then flow through the upper heating coil 30. This will continue until the heated water in the upper part of the tank has caused the tube 33 to expand sufficiently to lower the operating lever 44 to such an extent as to snap lever 86 to its lower position, when the contact 90 will engage button 69 on bolt 67. The circuit through coil 30 will thereby be broken, and a circuit will be set up from line wire 38 through snap lever 86 to contact 69 and bolt 67, thence through shunt bar 95 to screw 62, bracket 60 and contact button 70. Lever 85 being still in its upper position, current passes from button 70 to button 89 on the lever and thence through the lever and spring 83 to plate 74 and lip 91, through conductor 96 to lower heating coil 31, and through conductor 97 to line wire 37. The heating of the water in the lower part of the tank then continues until a predetermined temperature is reached, when the thermostat acts to lower lever 44 sufficiently to snap lever 85 to its lower position where it contacts with button 66, which is merely an insulated abutment. The circuit through the lower coil is thus broken.

In the event that only a small quantity of hot water is drawn from the tank, and a corresponding quantity of cold water is admitted beneath the thermostat, the latter will then raise the lever 44 a short distance sufficient to again snap lever 85 upwardly, returning it to contact with button 70. The circuit through lower heating coil 31 will therefore again be set up until the temperature is raised to the extent demanded by the thermostat, after which the latter will act to disconnect coil 31, as will be apparent.

Should the quantity of hot water withdrawn be considerable, the first effect will be to energize lower coil 31, but this effect will be only temporary or until the cold water entering the tank has reduced the temperature sufficiently to snap lever 86 also to its upper position, when coil 31 will be cut out and coil 30 will be cut in, whereupon the operation will be the same as above described for the condition where the current is turned on to heat a tank full of water.

In the foregoing description I have necessarily gone somewhat into detail in order to explain fully the particular embodiments of the invention herein illustrated, but I desire it to be understood that such detailed disclosures are not to be construed as amounting to limitations, except as they may be included in the appended claims.

Having thus described my invention, I claim:

1. In automatic control apparatus for a plurality of heating coils, a lever, thermostatic means for swinging the lever in response to temperature changes, a conductor lever for each heating coil, adjustable spring supports carried by said first named lever one for each of said coils, springs attached at their ends to said supports and said conductor levers adapted to hold said conductor levers in either on or off position, whereby the different adjustments of said spring supports will cause said conductor levers to snap from one extreme position to the other extreme position either simultaneously or one at a time at predetermined points in a given movement of the thermostat in response to rising or falling temperature.

2. In an automatic control apparatus for a pair of heating coils, two conductor levers pivotally mounted with their pivots in alignment, two spring supports movable transversely across the line of said pivots, two springs each attached at one end to one of said supports and at the other end to one of said levers, whereby the springs are adapted to hold the levers in either of two extreme positions, an element movable transversely of said line of pivots, said element being adapted to be so moved by thermostatic means in response to temperature changes, and means for adjustably connecting said supports to said element, whereby the conductor levers will snap from one extreme position to the other one at a time at predetermined points in a given movement of the thermostat in one direction.

3. In apparatus of the class described, means for moving an electric contact from operative to inoperative position and vice versa, comprising a lever, a coil spring on one side of said lever tending to hold it against movement in one direction, and a shaft extending through said spring threadably mounted in said lever and extending through the lever to form an abutment on the side opposite the spring for engagement with any suitable lever swinging element, whereby rotation of the shaft varies the adjustment of said abutment.

GORDON H. CLARK.
